ROTARY INTAGLIO PRINTING
MACHINE

Albert J. Horton, White Plains, N. Y., assignor to
R. Hoe & Co., Inc., New York, N. Y., a corpora-
tion of New York

Application April 28, 1936, Serial No. 76,802

15 Claims. (Cl. 101—157)

This invention relates to intaglio web printing machines, and more particularly to improvements in the construction of the same, whereby increased efficiency in the use and operation thereof will be obtained and various disadvantages and difficulties at present experienced will be obviated.

Considerable difficulty and various disadvantages are being experienced in the use and operation of intaglio web printing machines constructed 10 in accordance with present designs. Various constructions have been suggested and some are in use, wherein the ink fountain, in which, in this type of printing machine, the printing cylinder usually rotates in direct contact with the ink, is 15 entirely enclosed to prevent drying of the ink therein, necessitating some form of seal in contact with the surface of the cylinder. The sealing material, in such instances, picks up ink which, when dry, hardens and often scratches or 20 otherwise mars the cylinder surface causing undesired printed marks to appear on the printed web.

In intaglio printing machines, and especially those used in multi-color printing, provision has 25 been made for quickly drying the ink on the printed web before it passes to the next color printing cylinder. This may be accomplished by directing a stream of preferably heated air against the printed web and, where considered 30 necessary, by the additional use and application of heat to the web adjacent the point at which the air is directed. Such an arrangement has been developed in the form of a mechanism, wherein provision is made to pass the web 35 through a housing into which the air is directed against the web, and from which it is withdrawn. Much of the ink solvent vapor is collected and may be recovered by such an arrangement, but considerable vapor loss occurs from evaporation 40 of the solvent of the ink in the fountain, which evaporation is increased when the cylinder is being rotated, due to the agitation of the air adjacent thereto.

This invention contemplates as one of its objects, the provision of means to collect for recovery, the evaporated ink solvent normally lost by dissipation into the atmosphere from ink fountains that are not fully enclosed, such forms of fountains being considered preferable due to the 45 disadvantages occasioned in the use of sealed ones.

Another object is to provide in combination with a web drying and solvent removal mechanism, means for collecting the evaporated ink solvent from spaces about and adjacent to the print-

ing cylinder and the fountain, and directing it to a common outlet.

Still another object is to provide in combination with an ink fountain of an intaglio web printing machine, means to exhaust the solvent laden vapors forming about the printing cylinder while it is rotating in the fountain to prevent egress of these vapors from the fountain. 5

A further object of this invention is to provide in an intaglio printing machine, means to prevent air from being carried by the rotating printing cylinder into the fountain to contact with the ink therein and increase evaporation of the solvent therefrom. 10

It is also an object of this invention to provide an intaglio web printing machine of improved construction, whereby the same will be more convenient, practical, serviceable and efficient in its use, by the provision of simple, durable and inexpensive improvements thereto. 15

With the foregoing and other objects in view, which will appear as the description proceeds, the invention resides in the combination and arrangement of parts, and in the details of construction hereinafter described and claimed. 20

The preferred embodiment of the invention is illustrated in the accompanying drawings, wherein:

Figure 1 is a vertical transverse cross sectional view of an intaglio web printing machine embodying the features of this invention, the section being taken on line 1—1 of Figure 4; 30

Figure 2 is an enlarged sectional view of a portion of the machine shown in Figure 1 to more clearly show the construction thereof; 35

Figure 3 is a sectional view on line 3—3 of Figure 2;

Figure 4 is a front view of the web drying and ink solvent collecting device looking in the direction of arrow 4 in Figure 1; and 40

Figure 5 is a section of a cylinder end covering taken generally on line 5—5 of Figure 1.

Referring to Figure 1 of the drawings, there is illustrated an intaglio web printing machine as improved in accordance with the features of this invention. A frame 11 is provided and arranged to support a plurality of printing units, one only of which is shown, and includes an intaglio printing cylinder 12 and a co-operating impression cylinder 13. The impression cylinder 13 may be engaged by rollers 14 which reinforce the same during movement from the printing cylinder 12 during the printing operation. A plurality of web guiding rollers 15 are provided to guide a web 16 to the printing unit from another unit or 45 50 55

a web supply (not shown) and from the unit, over rollers 18 and 19, which may be heated if desired, and other rollers 21 in an arcuate path to a roller 23 which may be fluid cooled. From the roller 23, the web is directed over a roller 24 to another unit or toward the delivery mechanism of the machine. It will be understood that the cylinder 12 of the printing unit is driven by suitable means, not shown, in timed relation with the other operative parts of the machine.

10 An air drying device is provided, which includes a cylindrical hollow drum 25 having a transverse partition 26 therein (see Figure 4), for a purpose to be hereinafter described. Herein the opposite ends of the drum 25 are rotatably supported upon the anti-friction rollers 21, mounted on the machine frame 11. A stationary intake conduit 28 is connected to one end of the drum 25 and is in connection with a fan casing 29 through which it is connected with an air intake conduit 31. Steam pipes 32 may be provided and disposed in the conduit 31 to heat the air passing therethrough from a source of supply, not shown. The other end of the drum 25 is connected to an exhaust conduit 33 which is connected to another fan casing 34 and through it to an exhaust conduit 35. The conduit 35, in this instance, may be connected to an ink solvent recovery apparatus, not shown, the structure and operation of which is well known and forms no part of this invention. Suitably constructed blower type fans 36 and 37 are disposed in casings 29 and 34 respectively, and are rotated by a motor 38, mounted upon the frame 11.

A housing 41 extends downwardly from the drum 25 and is provided with a front wall 42 and a rear wall 43 (best shown in Figure 1). Between the front and rear walls 42 and 43, spaced apart partitions 44 and 45 are provided which form, with the walls 42 and 43 respectively, separate ducts 46, 47 and 48. The duct 46 formed by the front wall 42 and the partition 44 is in communication with the interior portion 49 of the drum 25 through an elongated opening 51, formed in the wall of the drum at the side of the partition 26 therein, which is in connection with the exhaust conduit 33. The duct 48 formed by the rear wall 43 and the partition 45 is in communication with the interior portion 49, through 50 an elongated opening 52, also formed in the wall of the drum 25. The duct 47, which is disposed substantially intermediate the ducts 46 and 48 and formed by the partitions 44 and 45, is in communication with the interior portion 53 of the drum 25 through an elongated opening 54 formed in the wall of the drum at the side of the partition 26 therein and which is in connection with the intake conduit 28.

60 A marginal flange 55 extends forwardly from the peripheral edge of the front wall 42 of the housing 41, and with the front wall 42 is shaped to conform to that portion of the web path defined by the rollers 18, 19 and 21 positioned between the printing unit and the roller 23. A back wall 50 extending behind the rollers 18, 19 and 21 serves to substantially complete the enclosure. By this arrangement, an air receptacle 56 is formed by the marginal flange 55, the front wall 42 and the back wall 50, when the housing 65 70 is swung into the position shown in full lines in Figure 1, from the dotted position shown therein, by rotation of the drum 25 upon the rollers 21. The air receptacle 56, so formed, is in communication with the duct 46 through an elongated passage 57 which extends substantially across the

entire width of the front wall 42 of the housing 41. The air receptacle 56 is in communication with the ducts 47 and 48 through similarly formed and elongated passages 58 and 59 respectively.

When it is desired to subject the running web 5 16 to the drying influence of air currents, the fans 36 and 37 are rotated to cause a flow of air from the conduit 31, through the fan casing 29 and conduit 28, into the interior portion 53 of the drum 25 and from the drum through the 10 opening 54, duct 41, and the passage 58 onto the web 16. The air upon striking against the web 16 spreads, partly due to the convex curvature thereof, and flows over the printed surface of the web, drying the ink by evaporation of the solvent 15 thereof. The solvent laden air or vapor is exhausted from the receptacle 56 through passages 57 and 59 into the ducts 46 and 48 respectively, from which it flows through openings 51 and 52 into the interior portion 49 of the drum 25 and 20 from there through the conduit 33, and the fan casing 34 into the exhaust conduit 35, by which it is directed to the solvent recovery apparatus, the fan 37 drawing the air or vapor from the receptacle 56 and advancing it into the conduit 35. 25 The arrangement is preferably one, whereby the fan 37 moves a somewhat greater volume of air than furnished by the fan 36 whereby a comparatively rapid flow of air is caused and a slightly rarified or partially exhausted condition exists 30 in ducts 46 and 48.

The printing cylinder 12 which is preferably journaled in the frame 11, rotates within an ink fountain 61 and collects ink upon its surface by being partly submerged in a supply of ink 62, 35 which is maintained at a constant level in the fountain 61 under the control of an overflow pipe 63, the ink being supplied from a suitable source through an intake pipe 64. A doctor blade 65 is provided to engage the cylinder 12 and remove 40 surplus ink from its surface before it engages the web 16 to print impressions thereon. Herein the doctor blade 65, carried in a blade holder 65', is swingably mounted upon a carriage 66 by pivoting a blade holder arm 67 thereto and is adapted to reciprocate lengthwise along the cylinder 12 by the sliding of the carriage 66 on ways 68. 45

A member 71, extending lengthwise of the ink fountain 61 from end to end thereof, is hinged to the fountain by pins 70 and carries a flexible 50 shield 72 engaging the blade holder 65'. At each end of the cylinder 12, arcuate flanges 74, which extend a short distance over and are spaced from the cylinder surface, are provided, (as best shown in Figure 5) and are formed integral with end plates 75 secured to cylinder shaft packing caps 75' provided at each end of the fountain 61 to prevent leakage of ink. The end plates 75 are spaced from the cylinder ends, the space therebetween at each end of the cylinder being in 55 communication with openings 73 under the doctor blade at the ends of the fountain. 60

As shown in Figure 2, a shield 76, secured to a cover plate 77, pivoted to the fountain 61 at 78 is provided, and with plate 77, extends along the 65 cylinder 12 from end to end thereof. The edges of both the shield 76 and the plate 77 are spaced from the surface of the cylinder 12 and these parts cooperate to provide a chamber 79 which is in communication with the openings 73 through 70 the spaces at each end of the cylinder 12 between the plates 75 and the adjacent cylinder end. A plurality of apertures 80 are provided in the cover plate 77 and are in communication with the chamber 79. The apertures 80 are spaced apart 75

longitudinally of the cylinder 12 and preferably are formed gradually smaller in diameter as they approach the end of the series.

As shown in Figure 3, a casing 81 is disposed upon and secured to the plate 11, extending completely the length thereof, and with it, forms a chamber 82, with which the chamber 79 is in communication by means of the apertures 80. At one end of the cylinder 12, the cover plate extends beyond the fountain 61 and at this extended portion 83, (see Figure 3) it is provided with an opening 84.

A nipple 85 is mounted in a bracket 86 secured to one end wall of the fountain 61, and provision is made by a sealing washer 87 to seal the joint between the nipple 85 and the cover plate portion 83, when the cover plate is in the position as shown in Figure 2. Another nipple 88, (see Figure 1) is mounted in a bracket 89 secured to the machine frame 11 and is provided with a sealing washer 91, whereby the joint between it and a sidewise extending portion 92, (see Figure 4) formed at one side of the housing 41, will be sealed when this housing is swung into the full line or operative position shown in Figure 1. The extending portion 92 is hollow and communicates with the duct 48 by means of an aperture 93. An aperture 94 formed in the exterior wall of the portion 92 communicates with the nipple 88. A pipe 95 having a shut-off cock 96 associated therewith, connects the nipples 85 and 88.

Due to the above arrangement, the openings 13, the chamber 79, and the spaces between each end of the cylinder 12 and the adjacent end plates 75 and flanges 74, are in communication through the apertures 80, chamber 82, nipple 85, pipe 95, nipple 88, and the hollow housing portion 92, with the duct 48, whereby air or solvent laden vapor will be drawn from the aforesaid chamber and spaces when the housing 41 is in operative position and the fans 36 and 37 are operating. The shut-off cock 96 may be actuated to adjust the exhausting effect on the chamber 79 and the end spaces. Exhaust of the air sufficient to cause a slight amount of fresh air to be drawn into these chambers through the spaces about the edges of the cover plate 11 and flanges 74 at 97 and 98 respectively, but not to draw vapor from the fountain 61, is preferable, and this can be controlled by the cock 96. A partial exhaustion of the vapor or air in the chamber 79 prevent fresh air from being carried into the ink fountain by the rotating cylinder 12, wherein it would absorb ink solvent and cause excessive drying of the ink.

By the provision of the above described means to maintain the several spaces and chambers in partially exhausted condition, whereby the solvent laden vapors are not permitted to escape into the atmosphere, permits the use of a printing unit wherein no sealing of the ink fountain is required with its attendant disadvantages. The immediate exhaust of the air drawn in through the space 97, by the rotating cylinder 12, also prevents the building up of pressure within the ink fountain which might result in the escape of solvent laden vapor through the desired clearance spaces about the cylinder. The collection of solvent laden vapor which normally is dissipated into the room atmosphere, and lost, and directing it to a solvent recovery apparatus decreases the loss of a comparatively expensive product, and therefore decreases the cost of the operation of a printing machine of this type,

and as the vapors of many of the solvents used are inflammable, the fire hazard is usually minimized. The prevention of evaporation of solvent from the fountain, especially the lower portion thereof, in which the ink is disposed, tends to maintain therein a body of ink solvent saturated vapor which prevents further evaporation, and therefore maintains the ink in its most efficient condition.

Obviously, additional connections between the fountain and the exhausting apparatus may be made when the fountain construction is such that the escape of the vapors cannot be prevented by the single connection as herein shown. Hence, it will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the device herein disclosed forms a part of the invention included in this application.

What I claim is:

1. In an intaglio printing machine, in combination, an ink fountain having in its structure upper and lower communicating compartments, a printing cylinder mounted to rotate in said ink fountain and take ink upon its surface from said lower compartment, said upper compartment being formed by a cover plate for the ink fountain and a wall below the cover plate, said plate and said wall ending adjacent said cylinder, said cover plate being mounted for movement to uncover said fountain and carrying said wall, and means to draw air from said upper compartment to prevent it entering said lower compartment.

2. In an intaglio printing machine, in combination, an ink fountain having in its structure upper and lower communicating compartments, a printing cylinder mounted to rotate in said ink fountain and take ink upon its surface from said lower compartment, said upper compartment being formed by a cover plate for the ink fountain and a wall below the cover plate, said plate and said wall ending adjacent said cylinder, said wall being secured to said cover plate and said cover plate being swingably mounted for movement to uncover said fountain, and means to draw air into said upper compartment from the atmosphere outside of said fountain and to exhaust this air out of said upper compartment, and thereby preventing the indrawn air from entering said lower compartment.

3. In an intaglio printing machine, in combination, an ink fountain having in its structure upper and lower communicating compartments, a printing cylinder mounted to rotate in said ink fountain and take ink upon its surface from said lower compartment, a wall spaced from each end of said cylinder to form a chamber therebetween which is in communication with the upper compartment, walls for said upper compartment ending adjacent said cylinder, one of said walls forming a cover plate for said fountain at one side of said cylinder and the other wall being in said fountain below the first wall, and means to prevent a flow of air from outside of said fountain between the walls of said upper compartment and said cylinder and the end walls and said cylinder from reaching said lower compartment.

4. In an intaglio printing machine, in combination, a printing unit including a printing

- cylinder, an end plate spaced from each end of said cylinder, a hinged cover plate having a wall secured to and extending below the plate, said plate and wall extending toward, ending 5 adjacent to, and extending lengthwise of, said cylinder to form a chamber, said chamber being in communication with each of the spaces between each cylinder end and said end plate adjacent thereto, an ink holding compartment below said chamber in which said cylinder rotates in contact with the ink therein, and air exhausting means in communication with said chamber to cause the air pressure therein to be slightly 10 below atmospheric pressure, and thereby cause 15 a flow of air into said chamber and the aforesaid spaces at the cylinder ends from the outside atmosphere.
5. In a printing machine, in combination, an ink holding fountain, a cylinder mounted to rotate in said fountain in contact with ink therein, a cover plate extending from a side of said fountain to adjacent the cylinder, a wall disposed below said plate and spaced therefrom, whereby 20 said fountain is divided into communicating upper and lower compartments, said cover plate and said wall forming the upper compartment being mounted for swinging movement to uncover said lower compartment, the upper one of 25 said compartments being in communication with the atmosphere outside of said fountain, and an air exhausting mechanism in connection with 30 said upper compartment when it is in position to cover the lower compartment.
6. In an intaglio web printing machine, in combination, a printing cylinder mounted for rotation in the fountain in contact with ink therein, an impression cylinder cooperating with the printing cylinder, an ink fountain partially enclosing the printing cylinder and including a 35 cover plate, means to guide a web to and from the said cylinders, ink drying means including an air exhausting duct adjacent the web after it leaves the cylinders, a first chamber below said cover plate and within the fountain and being 40 open adjacent the printing cylinder, a chamber at each end of the printing cylinder, each end chamber being in communication with the first chamber and a connection between said first chamber and said duct to draw air from said 45 chambers into said duct.
7. In a rotary intaglio printing machine, a covered ink fountain including a top cover plate, a printing cylinder supported to rotate within the fountain below said cover plate, said cover plate being movable to uncover said fountain, a chamber carried by said cover plate within the fountain and being open adjacent the printing cylinder, a plate spaced from each end of said cylinder to form end chambers, said end chambers being in communication with the chamber carried by said cover plate and an air exhausting 50 device connected to the chamber.
8. In an intaglio web printing machine, a covered ink fountain including a cover plate, a printing cylinder supported to rotate within the fountain, an enclosure through which the printed web is led, means for propelling air into the enclosure, exhausting means for withdrawing air from the enclosure, a chamber disposed below the cover plate and within the fountain, and a duct 55 operatively connected with said chamber and with the exhausting means.

9. In a rotary intaglio web printing machine, a covered ink fountain including a hinged cover plate, a printing cylinder supported to rotate within the fountain, an enclosure through which the printed web is led, an inlet duct and an exhaust duct each communicating with the enclosure, means for passing air through the ducts, a chamber carried by the cover plate and open adjacent the cylinder, and a connection from said chamber to the said exhaust duct. 10

10. In a rotary intaglio machine for printing on paper, an ink fountain, a printing cylinder supported to rotate within the fountain, covering means for the fountain extending close to the form cylinder, an enclosure through which the printed paper is led, means for passing air through the enclosure to dry ink on the printed paper, said last mentioned means including an inlet duct and an exhaust duct communicating with the enclosure, a chamber associated with the fountain, and a connection from said chamber to the said exhaust duct, whereby the fluid pressure within the fountain may be maintained slightly below atmospheric pressure.

11. In a printing machine, a cylinder, an ink holding fountain extending about said cylinder and partially enclosing the same, a chamber extending lengthwise of and open adjacent to said cylinder and being hinged to the upper edge of said fountain, and air exhausting means connected to the chamber.

12. In a printing machine, a cylinder, an ink holding fountain extending about said cylinder and partially enclosing the same, a chamber mounted to be swung into and out of said fountain, said chamber having an open side adapted to be disposed adjacent the cylinder when the chamber is within the fountain, and means to exhaust air from the chamber.

13. In a printing machine, a cylinder, an ink holding fountain extending about said cylinder and partially enclosing the same, a first chamber extending lengthwise of and open adjacent to said cylinder and being hinged for swinging movement toward and away from said cylinder, a second chamber at each end of said cylinder in communication with said first chamber, and means connected to said first chamber to exhaust air from said second chambers.

14. In a printing machine, a cylinder, an ink holding fountain extending about said cylinder and partially enclosing the same, a first chamber extending lengthwise of and open adjacent to said cylinder and being hinged for swinging movement toward and away from said cylinder, a second chamber at each end of said cylinder in communication with said first chamber, air exhausting means, and means to connect said first chamber to said air exhausting means when said first chamber is moved to a position adjacent said cylinder.

15. In a printing machine, a cylinder, an ink holding fountain extending about said cylinder and partially enclosing the same, a chamber extending lengthwise of and open to said cylinder and being hinged to the upper edge of said fountain, air exhausting means, and means to connect said chamber to said air exhausting means only when said chamber is in position adjacent said cylinder.

ALBERT J. HORTON.
